UNITED STATES PATENT OFFICE.

RAYMOND WOLK, OF ST. LOUIS, MISSOURI.

REEL.

Application filed July 27, 1925. Serial No. 46,322.

To all whom it may concern:

Be it known that I, RAYMOND WOLK, a citizen of the United States, residing at St. Louis, Missouri, have invented a new and useful Reel, of which the following is a specification.

This invention relates to reels of the type adapted for use as portable hand reels in the winding of clothes lines, and the like.

10 An object of the invention is to provide an improved portable hand reel capable of use in winding clothes lines and the like, and comprising a hub including a number of longitudinal pieces attached to strengthening blocks and to end pieces serving as the flanges of the reel, one of which has a handle attached thereto, in combination with an axle member extending rotatively through one of the end pieces and through the blocks 15 of the core into contact with the opposite end piece, which limits longitudinal movement of the axle member in one direction, and means for preventing withdrawal of the axle member.

25 Another object of the invention is to provide an improved reel of the character and approximate structure mentioned in which the parts are readily detachable for purposes of repair.

30 Other objects of the invention will appear from the accompanying description taken in connection with the drawing, in which

Fig. 1 is a side elevation of my improved reel with certain parts in section to illustrate the relationship of the axle member to the other parts.

Fig. 2 is an end elevation from the end beyond which the axle member extends.

Fig. 3 is an elevation of the opposite end 40 of the reel.

Fig. 4 is a cross sectional view on the line 4—4 of Fig. 1.

My improved reel consists of a pair of ends 1 and 2 of approximately equal length 45 and having their extremities at right angles to their side edges, so that they will stand upright and support the windings on the reel out of contact with the floor or surface upon which the reel is supported.

50 A polygonal block 3 is attached to the end 1 by glue and by nails 4; and a polygonal block 5 is similarly attached to the end 2 by glue and by nails 6. Each of the blocks 3 and 5 is bored to form a round hole in 55 which an axle handle member 7 is rotatively mounted, the handle member 7 also ex-

tending through a round hole in the end 2 and having its opposite end abutting against the inner side of the end 1 and thereby limited from longitudinal movement in one direction.

60 The blocks 5 have their polygonal sides in the same planes, and a number of cross bars 8 are glued thereto and additionally fastened by nails 9.

An intermediate block 10 matching the 65 blocks 3 and 5 is glued to the inner sides of the bars 8 midway between the ends 1 and 2, and additional rigidity is obtained by nails 11 driven through the bars 8 and into said block 10. A withdrawable staple 12 70 is forced into the axle 7 on the side of the block 10 toward the end 1 and prevents withdrawal of said axle 7 from the reel.

A handle 13 is attached to the outer surface of the end 1 by a fastener 14 and extends in a plane parallel with the axis of the axle 7 and serves as a crank to co-operate with the axle 7 to rotate the reel in winding.

75 Rigidity for the handle 13 is obtained by 80 a block 15 attached to the end 1 by glue and by nails 16. The block 15 has a hole in which the handle 13 is fitted.

85 From the foregoing it will be seen that my invention obtains all of its intended objects and purposes in a highly efficient and simplified manner, and is capable of application to many useful purposes and of variation within equivalent limits without departure from the nature and principle 90 thereof. I do not restrict myself unessentially, but what I claim and desire to secure by Letters Patent is:—

1. A reel comprising a pair of parallel ends, a block attached to the inner side of 95 each of said ends and having a central hole therethrough, a number of bars attached to said blocks and abutting against said ends, an intermediate block attached to said bars and having a hole therethrough in alignment with the holes through said first named blocks, an axle member extending rotatively through one end and through the holes in all of said blocks and abutting against the opposite one of said ends, and a handle attached to said opposite end.

100 2. A reel comprising a pair of parallel ends, a number of bars rigidly supported between said ends, an axle member extending through one end of the reel and extending longitudinally between said bars 110

- and having one end abutting against the opposite end of the reel, means preventing withdrawal of said axle, and a handle attached to said opposite end of the reel.
- 5 3. A reel comprising a body portion, a pair of parallel ends supporting said body portion, an axle rotatively extending through one of said ends and through said

body portion and abutting against the opposite end of the reel and having one end projecting beyond said end of the reel through which said axle extends, means preventing withdrawal of said axle, and a handle attached to the opposite end of the reel. ¹⁰
